MEANS FOR MINIMIZING INDUCTIVE INTERFERENCE.

1,196,303.

Specification of Letters Patent.

Patented Aug. 29, 1916.

Application filed January 2, 1915. Serial No. 173.

To all whom it may concern:

Be it known that I, CHARLES F. SCOTT, a citizen of the United States, and a resident of New Haven, in the county of New Haven and State of Connecticut, have invented a new and useful Improvement in Means for Minimizing Inductive Interference, of which the following is a specification.

My invention relates to means for minimizing and neutralizing disturbances in electrical circuits, such as intelligence-transmission circuits, which may be caused by electromagnetic induction arising from other circuits located in proximity thereto.

More particularly, my invention relates to improvements in means for protecting telephone, telegraph and other circuits which are utilized for the transmission of intelligence, and which are under the inductive influences of, and may be unequally spaced throughout their length from, other circuits utilized for the transmission of power by alternating currents.

Ordinarily, by confining the return flow of trolley currents to the track of a railway system, as explained in my patent application, Serial No. 170, filed concurrently herewith and assigned to the Westinghouse Electric & Manufacturing Company, the return currents and the trolley currents may be disposed closely adjacent to each other in order that the inductive disturbances arising from one circuit may be substantially neutralized by the inductive disturbances arising from the other circuit. However, in many installations, one or more telegraph or telephone circuits may be paralleled for longer or shorter distances by a plurality of trolley conductors and their associated track rails. In addition, the relative disposition of the different circuits may vary throughout, thus effecting a flow of unbalanced disturbing currents in the telegraph or telephone circuits.

It is often desirable to operate with two tracks connected in parallel so that they may divide the return current between them. If the outgoing current traverses the trolley conductor adjacent to the telegraph or telephone circuit, the conditions of induction are obviously different from those which prevail when the current flows through the remote trolley conductor, as the return current is divided substantially equally between the two tracks in both cases.

By means of my invention, I inductively interlink all of the circuits utilized for the transmission of power currents, and I provide means also for so adjusting the relative currents flowing in the various conductors, including the earth, as to neutralize or minimize the disturbances impressed upon adjacent telegraph or telephone circuits. Moreover, by means of my invention, the cost of protecting telegraph and telephone circuits and the like from inductive disturbances arising from a number of power-transmission circuits disposed adjacent to the telegraph and telephone circuits, may be reduced to a low figure.

For a better understanding of the nature and scope of my invention, reference may be had to the following description and the accompanying drawing in which—

Figure 1 is a diagrammatic view of a system embodying a form of my invention; Fig. 2 is a diagrammatic view of a modification of the system shown in Fig. 1, and Fig. 3 is a diagrammatic representation of a form of transformer which I desire to utilize in my system.

Referring to Fig. 1, a source of power supply 1, shown as a single-phase alternator, is connected, through one terminal, to trolley conductors 2 and 3, and, through the other terminal, to track rails 4 and 5 which are associated with the trolley conductors 2 and 3, respectively. A plurality of transformers 6, the construction of which will be subsequently explained, are inserted at intervals along the railway system, as shown, primary windings 7 and 8 being connected in series-circuit relationship with the trolley conductors 2 and 3, and secondary windings 9 and 10 being connected to the rails 4 and 5, respectively, and across insulating joints 11. The insulating joints 11 divide the rails 4 and 5 into a series of track sections which are insulated from one another. An intelligence-transmission conductor 12, shown as a telegraph conductor, is disposed adjacent to the trolley conductors 2 and 3 and is, therefore, under the inductive influences arising from the currents flowing therein. In actual installations, however, the telegraph conductor 12 may be unequally spaced for longer or shorter distances from the trolley conductors and their associated track rails. Consequently, the electromotive forces impressed upon the telegraph cir-

cuit will vary at different points along its length, and, to this end, it is essential to impress neutralizing electromotive forces thereupon which will be of such amounts and of such character as to substantially preclude the flow of unbalanced currents over long distances in the telegraph conductor 12.

As explained in my other patent application which I have mentioned above, the return trolley currents are confined to the track rails 4 and 5 by reason of inductively interlinking the trolley conductors and the track rails. In this manner, the return trolley currents are maintained in close proximity to the trolley conductors, and the inducing disturbances arising from one will be substantially neutralized by the inducing disturbances arising from the other. The telegraph conductor 12, being unequally spaced from the different power conductors, will be under varying inducing influences. In order to compensate for these unbalanced inductive disturbances, each of the primary windings 7 and 8, and each of the secondary windings 9 and 10, may be provided with a plurality of taps 13 by means of which the current flow in the various conductors may be so controlled and proportioned as to impress the proper electromotive forces upon the telegraph conductor 12. If conditions are predetermined, however, the windings of the transformers may be provided with the precise turns desired, without supplying any taps.

As shown in Fig. 3, the four transformer windings 7, 8, 9 and 10 are wound on the same magnetic core structure 14. By this means, a single transformer may be utilized for two or more trolley conductors and their associated tracks in place of individual transformers for each trolley conductor and its associated track. However, current flowing in one trolley conductor will necessitate a return flow of current in both tracks by reason of both circuits being connected together, as previously explained. By means of the taps 13, the return currents flowing in the several tracks may be so adjusted as to neutralize the various electromotive forces impressed at different points on the telegraph conductor 12 by the trolley currents. At the same time, the windings interlinking the trolley conductors and the tracks may be embodied in single transformers, thereby greatly decreasing the cost of installing my system.

If the conditions are known, the number of turns comprising the transformer windings may be predetermined thereby eliminating the use of taps for adjusting the number of turns in the several windings. While a proper adjustment of the relative turns of the primary and secondary windings of the transformer 6 may be sufficient for reducing

ordinary disturbances impressed upon the circuit 12, it may be frequently desirable to adjust the phase relationship of the ground currents which, in common with the currents flowing in the track rails, constitute the return flow of the trolley currents and, in addition thereto, the magnetizing currents of the transformers 6. To accomplish this refined adjustment, the secondary windings 9 and 10 are each provided with artificial loads comprising adjustable resistors 15 and adjustable impedance devices 16. The resistors 15 and the impedance devices 16 are connected in series relationship with each other, and in shunt to the active turns comprising each secondary winding. The auxiliary circuits comprising the resistors and the impedance devices correspond to the ground circuit, and the phase and current conditions obtaining within these auxiliary circuits are substantially reproduced in the ground circuit.

While I have shown and described, in detail, an embodiment of my invention, it will be understood by those skilled in the art that many modifications may be made without departing from the spirit and scope of the appended claims.

I claim as my invention:

1. A system of distribution comprising a source of current supply, a set of conductors connected to one terminal thereof, a second set of conductors connected to the other terminal, a plurality of spaced series transformers inductively interlinking said sets of conductors, each transformer having a single core member and primary windings inserted in series circuit relationship with said first set of conductors and secondary windings inserted in series circuit relationship with said second set of conductors, and adjustable means to proportion the return current flow in one of said sets of conductors.

2. A system of distribution comprising a source of current supply, a plurality of conductors connected to one terminal thereof, a plurality of conductors connected to the other terminal, said second conductors being provided with a plurality of correspondingly spaced insulating joints, a plurality of spaced transformers inductively interlinking all of said conductors with one another, each transformer having a single core member, primary windings upon which are inserted in series-circuit relationship with said first conductors and secondary windings upon which are connected to said second conductors across said insulating joints therein, and means to proportion, at will, the return current flow in said second conductors.

3. A railway system comprising a source of current supply, a plurality of trolley conductors connected thereto, a plurality of

- tracks, spaced transformers to inductively interlink all the tracks with all the trolley conductors, and means serving to proportion the current flow in each track.
- 5 4. A railway system comprising a source of current supply, a plurality of trolley conductors connected thereto, a plurality of track circuits in contact with the earth, each of which comprises a series of conducting rail sections insulated from one another, and spaced transformers having a common core and primary windings thereon which are connected in series circuit with each trolley conductor and secondary windings which are connected to adjacent rail sections of each track.
- 10 5. A railway system comprising a source of current supply, a plurality of trolley conductors connected thereto, a plurality of tracks in contact with the earth each of which comprises a series of conducting rail sections insulated from one another, spaced transformers having a common core and primary windings thereon which are connected in series circuit with each trolley conductor and secondary windings which are connected to adjacent rail sections of each track, and means serving to proportion the current flow in each track and the earth.
- 15 6. A railway system comprising a source of current supply, a plurality of trolley conductors connected thereto, a plurality of tracks in contact with the earth each of which comprises a series of conducting rail sections insulated from one another, spaced transformers having a common core and primary windings thereon which are connected in series circuit with each trolley conductor and secondary windings which are connected to adjacent rail sections of each track, and means serving to proportion the current flow in each track.
- 20 7. A railway system comprising a source of current supply, a plurality of trolley conductors connected thereto, a plurality of tracks in contact with the earth, each of which comprises a series of conducting rail sections insulated from one another, spaced transformers having a common core and primary windings thereon which are connected in series circuit with each trolley conductor and secondary windings which are connected to adjacent rail sections of each track, and means serving to proportion the current flow in each track and the earth.
- 25 8. A railway system comprising a source of current supply, a plurality of trolley conductors connected thereto, a plurality of tracks in contact with the earth, each of which comprises a series of conducting rail sections insulated from one another, spaced transformers having a common core and primary windings thereon which are connected in series circuit with each trolley conductor and secondary windings which are connected to adjacent rail sections of each track, means serving to proportion the current flow in each track and the earth, and means to adjust the phase relationship of the earth currents.
- 30 9. In testimony whereof, I have hereunto subscribed my name this 23rd day of Dec. 1914.
